US0D1062707S

(12) **United States Design Patent** (10) **Patent No.:** **US D1,062,707 S**
(45) **Date of Patent:** **** Feb. 18, 2025**

(54) **MOBILE PHONE**

(71) Applicant: **JRD COMMUNICATION (SHENZHEN) LTD.**, Shenzhen (CN)
(72) Inventors: **Zhihua Wan**, Guangdong (CN); **Liangjian Chen**, Guangdong (CN); **Wei Yang**, Guangdong (CN); **Fuqiang Ye**, Guangdong (CN); **Yan Zhu**, Guangdong (CN)
(73) Assignee: **JRD COMMUNICATION (SHENZHEN) LTD.**, Guangdong (CN)
(**) Term: **15 Years**

(21) Appl. No.: **35/519,958**

(22) Filed: **Dec. 20, 2023**

(80) **Hague Agreement Data**

Int. Filing Date: **Dec. 20, 2023**
Int. Reg. No.: **DM/234834**
Int. Reg. Date: **Dec. 20, 2023**
Int. Reg. Pub. Date: **Feb. 9, 2024**

(57) **CLAIM**

The ornamental design for a mobile phone as shown and described.

DESCRIPTION

The file of this patent contains at least one drawing/photograph executed in color. Copies of this patent with color drawing(s)/photograph(s) will be provided by the Office upon request and payment of the necessary fee.

1. Mobile phone
1.1 : Front
1.2 : Back
1.3 : Left
1.4 : Right
1.5 : Top
1.6 : Bottom
1.7 : Perspective
1.8 : Perspective

FIGS. 1.1-1.8 show an embodiment of a mobile phone; The dark blue and yellow coloring shown in the drawings are for the purpose of illustrating portions of the mobile phone which form no part of the claimed design. Portions of the mobile phone shown in light blue, black, gray, and white are included in the claim.

1 Claim, 8 Drawing Sheets
(8 of 8 Drawing Sheet(s) Filed in Color)
